METAL SHOE

Filed May 31, 1930

UNITED STATES PATENT OFFICE

PAUL BURDOTTI, OF NEW YORK, N. Y.

METAL SHOE

Application filed May 31, 1930. Serial No. 457,961.

My invention relates to shoes constructed of metallic material.

One object of my invention is to provide metallic shoes having the flexibility ordinarily required for comfort and sufficient resiliency to return to unstressed condition after being flexed.

Another object is to provide a shoe at low cost which fills the requirements of the wearer for comfort, and which is adapted to retain its shape and wear for a longer period of time than the ordinary leather shoe.

In the drawing:

Fig. 1 is a perspective of one form of shoe constructed according to and embodying my said invention;

Fig. 2 is a central section taken on the line 2—2 of Fig. 1;

Fig. 3 is a perspective of the upper; Fig. 4 is a reduced inverted plan showing a scroll of fancy design, letters or the like engraved, cut or stamped into the surface of the sole to prevent slipping; and

Fig. 5 is an enlarged section taken on the line 5—5 of Fig. 1;

Referring to the drawing 10 represents the shoe as a whole which comprises six major parts, namely, a combined metal counter and upper 12, a flexible mesh member 14, a toe cap 16, sole 18, welt like binding strip 20 and heel lift 22.

The portion 12, preferably stamped and formed from light gauge metal as indicated at Fig. 3, includes a curved portion 24 of relatively stiff metal formed to fit the heel, forwardly extending portions 26—26 of greater flexibility, and at the lower edge thereof, an inwardly directed flange 28 and short outwardly directed flanges 30 in advance of the flange 28. The portions 26, 26 do not extend the full length of the shoe down to the toe, but only about two-thirds thereof.

The sole 18 is formed with a flat flexible forward portion 32, an arch 34 and a heel portion 36 which fits over the flange 28 of the

counter 12. The hollow heel lift 22 having inwardly directed flanges 38, is secured directly beneath the heel portion 36 of the sole 18. The toe cap 16, provided with outwardly directed flanges 17, is next placed in position over the sole at the forward end.

The sole as thus far described is composed of stamped or sheet metal parts forming the main body of the shoe.

If the shoe were fabricated entirely of stamped metal, it would be stiff and uncomfortable. To avoid this I provide a flexible wire mesh member 14, which serves as a lining inside the portion 12, and extends to the end of the toe cap 16, and serves also as a lining for the toe. The upper portion of the shoe as a whole, between the forwardly-extending portions 26, 26 and the toe cap is then composed solely of the metallic mesh material 14, and this portion of the upper part of the shoe directly above the ball of the foot, for the purposes of this description and claims, shall hereinafter be referred to as the vamp, as at 23, Figs. 1 and 2. The lower inwardly directed edge portion 13 at the rear of the shoe is secured between the portion 36 of the sole, and flange 28 of the counter, while the outwardly directed edge portion 15, forward of the heel 22, is secured by the binding strip 20 which has an undercut portion 42. The said binding strip is secured around the edge of the sole, the free ends terminating over the outwardly directed flanges 30.

When the wearer is walking, a shoe receives most of the bending strain at the vamp between the instep and the toe cap 16. As stated, the metallic mesh lining 14 covering this area is therefore here utilized as such vamp, as indicated at 23, providing the flexibility required for the purpose while retaining its original appearance after extended wear.

After all of the parts have been properly assembled on a form of any convenient type, such as a last or the like, the same are secured

in any convenient way, as for instance by the process of welding.

The welding line will be along the binding strip 20 and the sole 18 to secure the parts together continuously coextensive with the line of juncture thereof to form a fluid-tight joint to prevent entrance of moisture, the rear ends of the portion 20 being also welded to the flanges 30. The heel 22 and contiguous parts 13, 28 and 38 are then suitably welded together in the manner to produce a fluid-tight joint. Next the edge 19 of the toe cap, is welded to the mesh as is also the edge 21 of the portion 26.

15 The mesh member 14 is woven closely from fine wire providing a part having smooth inner and outer surfaces adapted to serve as a lining for the shoe as well as a smooth flexible vamp 23. A portion 27 of the lining 20 over the instep is extended across a gap between the portions 26—26 to form a tongue over which the shoe is laced or otherwise fastened. This portion is preferably more loosely woven to permit of the same temporarily yielding when the shoe is being put on. A portion 25 on the counter 12 is turned down over the upper edge of the mesh 14 and rolled smooth as shown in Fig. 2 to secure the upper edge of the mesh to the counter, and 30 spot welding may be employed if so desired.

After the welding operation, a heel 44 of relatively greater yieldability such as rubber or leather is attached to the hollow heel 22 in any convenient manner, as for instance by screws 46 shown in Figs. 2 and 4, such yieldable heel, together with the flexible sole insuring great ease in walking.

Any means may be employed to fasten the shoe, such as for instance laces of woven wire, 40 fabric or leather, as shown in the drawing, or the usual clamps, buckles or the like, the forward ends 26 of the counter or upper 26 being altered according to the fastening means employed.

45 The shoe embodying my said invention is adapted for light dress wear for men or women, for the working man who is ordinarily obliged to wear heavy and clumsy leather shoes, or for use by foundry men, steel workers or workmen who handle molten metal.

The surface of the shoe can be japanned, enameled or plated to provide a luster far superior to the polish on a leather shoe.

50 To prevent slipping the sole of the shoe may be roughened, if so desired, by means of sand blasting, corrugating or by stamping or cutting a fancy design such as a scroll or letters as shown in the drawing in Fig. 4.

60 The mesh vamp 23, particularly if left uncoated, provides ventilation.

Having described my invention what I claim and desire to secure by Letters Patent is:

65 1. As an article of manufacture, a shoe

comprising a metallic sole and heel, and flexible metallic upper portions adapted to be drawn towards each other for fastening the shoe on the foot, the upper portions of the shoe lined with a metallic mesh material, but with the vamp of said shoe consisting solely of said metallic mesh material. 70

2. A shoe comprising a flexible metal sole, a hollow metal heel, a metal counter and upper, forming the rear portion of the shoe, a metal cap, and a metal mesh member between said rear portion and said cap. 75

3. A shoe comprising a flexible metal sole, a hollow metal heel, a metal counter with flexible forwardly extending end portions, means for fastening said end portions together, a metal cap and a more flexible metal portion between said counter and said cap. 80

4. A shoe comprising a flexible metal sole, a hollow metal heel, a metal counter and upper, forming the rear portion of the shoe, a metal cap, and a metal mesh lining having an 85 expandible tongue portion.

5. A shoe comprising a metallic sole and heel, a combined counter and upper portion 90 of metallic material, a metallic toe cap, and a lining of metallic mesh for said counter and upper portion and said cap and forming an intermediate relatively flexible vamp.

6. A metallic shoe line, except for the 95 vamp, with a mesh material, comprising a flexible metallic shoe and heel, an integral metallic portion forming a relative stiff counter merging into a relatively flexible upper, and means for fastening the free edges of the upper together, with the vamp of said shoe 100 consisting solely of said mesh material.

7. A metallic shoe completely lined, except for the vamp, with a metallic mesh material, comprising a flexible metal sole, a heel of metallic material, and a lift secured to said heel composed of relatively yieldable material, the vamp of said shoe consisting solely 105 of said metallic mesh material.

8. A shoe comprising a flexible metal sole, a hollow metal heel with inwardly directed flanged portions, a metal counter having an inwardly directed flanged lower portion received between said heel flange and heel portion of the sole and outwardly directed flanged portions, a metal toe cap, a metal mesh lining for said counter and toe cap, and having an exposed section therebetween forming a vamp, and a metal member for binding the lower edge of the mesh member and toe plate to the sole, the binding member terminating on said outwardly directed counter flanges, the parts being sealed together by welding to form a fluid tight joint at the line of juncture thereof. 110

9. A shoe comprising a flexible metal sole, a hollow metal heel, a metal counter with flexible forwardly extending end portions, an 115 expandible metallic tongue therebetween, means for fastening said end portions to 120

gether, a metal cap, and a flexible metal portion between said counter and cap.

10. As an article of manufacture, a shoe made entirely of metallic material, comprising a flexible sole, heel, counter and upper portion, and toe cap, and an inner lining for the toe cap and counter of said shoe of metallic mesh material, the vamp of said shoe consisting also of metallic mesh material.

10 In testimony whereof, I have signed my name hereto.

PAUL BURDOTTI.
